MARKER LIGHT

Ralph Higgins, Akron, Ohio, assignor to The Ohio
Brass Company, Mansfield, Ohio, a corporation
of New Jersey

Application October 10, 1932, Serial No. 637,108

11 Claims. (Cl. 177—352)

This invention relates to lighting systems, and particularly to markers for electrical transmission lines and other structures to warn aviators of the presence of these structures.

5 One object of the invention is to provide a marker which shall be economical to manufacture and operate and effective in service.

A further object of the invention is to provide 10 a marker which can be energized directly from the voltage on the transmission line and which can be applied to high potential transmission lines without interfering with the operation of the line.

Other objects and advantages will appear from 15 the following description.

The invention is exemplified by the combination and arrangement of parts shown in the accompanying drawing and described in the following specification, and it is more particularly 20 pointed out in the appended claims.

In the drawing:

Fig. 1 is a vertical sectional view of one form 25 of marker embodying the present invention.

Fig. 2 is a transverse section on line 2—2 of Fig. 1.

Fig. 3 is an elevation of a portion of a transmission line and its supporting insulator, showing the marker applied to the line; the figure being on a smaller scale than Figs. 1 and 2.

30 Fig. 4 shows the marker applied to the transmission line supported on a pin type insulator.

Fig. 5 is a view similar to Fig. 2 showing a modified clamp for securing the marker to the line.

35 Fig. 6 is a side elevation partly in section of the modification shown in Fig. 5.

In the form of the invention shown in Figs. 1, 2 and 3, the numeral 10 designates a high potential transmission line having capacitance members 11 and 12 mounted thereon by clamps 13 and 14, the capacitance members being insulated 40 from the transmission line by insulators 15, 16, 17 and 18. Spring clips 19 and 20 are connected with the insulators 15 and 16 and form

45 the terminals for a lighting element 21. The lighting element is preferably a neon tube or other gas filled tube which can be illuminated by a small current. It will be noted that the clip 20 is electrically connected to the clamp 13 and 50 insulated from the capacitance member 11, while the clip 19 is electrically connected to the capacitance member 11 and insulated from the transmission line. By this arrangement, charging current for the capacitance member 11 will flow

55 through the tube 21 and illuminate the tube. A

similar lighting element 22 may be connected to the capacitance member 12. The capacitance members 11 and 12 are made of open-work structure so that the light will shine through these members.

It will be seen that the lighting element can be mounted directly on the line and requires no external or ground connection, so that it in no way interferes with the operation of the line or affects the insulation of the line. In fact, where 10 the lighting element is mounted near the supporting structure, as shown in Fig. 3, the capacitance members 11 and 12 have the effect of increasing the diameter of the conductor so as to cut down corona and reduce the tendency to discharge between the transmission line and the supporting structure, as shown in Figs. 3 and 4. This device may also be mounted on any of the high voltage 15 conductors between supports in mid span. This is very important where high voltage lines span 20 a valley, creating a hazard for airplanes flying through the valley, that these lines be effectively marked.

Instead of supporting the insulators on clamps 13 and 14 held to the line by clamping bolts, a 25 spring clamp may be provided for mounting the device on the line, as shown in Figs. 5 and 6. In this case the insulators 15, 16, 17 and 18 are mounted on the jaws of spring clamps 23 so that the device may be readily applied to the line by 30 simply opening the jaws of the clamps, by means of insulating tongs, and applying them to the line 10, while the same is alive. Instead of using a spring clamp, the insulators 15, 16, 17 and 18 may be mounted on other standard live line 35 clamps. It is apparent that either form of device may be readily applied to transmission lines already in service and may be detached if desired with very little effort and no change in existing means of high voltage transmission line installation.

40 In this device, advantage is taken of the fact that the charging current from an energized conductor is much greater next to the conductor, due to the stray field effect. Thus, a small area of the 45 capacitor 11 and 12 is much more effective than a far larger area next to ground in producing sufficient charging current to light the vapor tube.

In the operation of vapor tubes, the initial or 50 starting voltage required to light the tube is quite high as compared to the voltage required to maintain its illumination current. With the capacitors 11 and 12 mounted near the live conductor, as shown in this device, a very high potential will 55

exist between the conductor 10 and the capacitors 11 and 12 when the tube is dark and taking practically little or no current; hence, it is seen that the tube will have a ready and effective source to furnish it with the required starting voltage. Once the tube is lighted and the flow of current established, this potential between the conductor 10 and capacitors 11 and 12 will drop to a low value, depending upon the amount of current, which in turn is limited by charging current from the capacitors 11 and 12.

It has been found that atmospheric static, or static induced from other near-by high voltage conductors, will be sufficient to give the tubes of this device a flickering illumination, due to the high frequency nature of this static, even when the conductor 10 is not energized from its normal source of supply.

In some cases it may be of advantage to connect the two capacitors 11 and 12 together by the jumper 37. When this is done, only one tube, the one having the lowest initial or starting voltage, will light up. This one will then take the charging current of both capacitors 11 and 12 as the other tube will not have a chance to light, due to the fact that the potential between the conductor 10 and capacitors 11 and 12 will immediately drop as soon as the first tube lights. In time, when this tube becomes burnt out or becomes defective, the other tube will then become operative. This tube then can be classed as a spare tube, and if its location is known or purposely made the lower one in position, the service man can take note of this fact and replace the former tube before both tubes become defective. In case both tubes become defective, a static discharge will be likely to take place between the conductor 10 and capacitors 11 and 12, across the shortest striking distance or over the surface of the insulators 16 and 17. This will be likely to cause a serious radio interference. To remedy this situation, it may be desirable to bridge these insulators with resistors 38. The resistance of these can be high enough so as not to rob the tubes of too much current while they are in operation, yet will be sufficient to furnish the capacitors with enough charging current to prevent any discharge taking place.

Another important use for this device when mounted on high voltage conductors and other live apparatus, as bus bars in power houses or sub-stations, is that it will serve as a means of voltage indications, showing that these parts are alive, for the convenience of operators, linemen and others.

Figs. 6 and 7 show a lighting element adapted for installation on a supporting tower or other structure, as shown in Fig. 8. In these figures, a pair of lighting elements 24 is shown having one end connected to a terminal clip 25 mounted directly on the supporting base, as shown in Fig. 6. An insulator 26 supports a terminal member 27 for the other ends of the lighting elements 24, and the terminal member 27 is provided with a supply conductor 28. A short-circuiting switch 29 may be provided for grounding the terminal 27 and cutting out the lights 24 when it is desired to change the lights or perform other operations on the installation.

In Fig. 8 the conductor 28 in the left hand side of the figure is connected through a spring 29 to a point 30 along the string of insulators 31 which supports the conductor 32. It will be seen that the lighting elements 24 in this case are subjected to a voltage corresponding to the voltage drop

over the insulator units between the point 30 and the supporting structure 33. The lighting elements 24 in the right hand side of Fig. 8 are connected by the conductor 28 to a capacitor plate 34 mounted on the supporting structure in inductive capacitance relation to the conductor 35. The plate 34 is insulated from the grounded structure by insulators 36. It will be apparent that the plate 34 will have a potential induced therein between the potential of the grounded structure 10 and that of the transmission line 35, the potential depending upon the position of the plate 34 relative to the grounded structure and transmission line. Charging current for the plate 34 will flow from the grounded structure through the lighting elements 24 and the conductor 28.

I claim:

1. The combination with a high voltage transmission line conductor, of an open-work capacitance member of conducting material disposed adjacent said conductor but insulated therefrom, and a lighting element disposed at one side of said capacitance member in position to shine therethrough and electrically connected between said conductor and open-work capacitance member and energized by charging current flowing between said conductor and capacitance member.

2. The combination with a high voltage transmission line conductor, of an open-work capacitance member mounted on said conductor but insulated therefrom, and a lighting element of the gas filled tube type disposed within said capacitance member and electrically connected between said conductor and capacitance member, and energized by charging current flowing between said conductor and capacitance member.

3. The combination with a transmission line conductor and its supporting structure, of an open-work capacitance member mounted on said conductor adjacent said structure but insulated from said conductor and from ground and having an extended surface transverse to lines normal to the axis of said conductor, and a lighting element of the gas filled tube type disposed at one side of said capacitance member in position to shine therethrough and electrically connected between said conductor and capacitance member and energized by charging current flowing between said conductor and capacitance member.

4. The combination with a transmission line conductor, of a pair of insulators mounted on said conductor, an open-work cage of conducting material mounted on said insulators, and a lighting element mounted on said conductor beneath a portion of said cage, and electrically connected between said conductor and cage.

5. The combination with a transmission line conductor, of a marker removably mounted on said conductor, said marker comprising a capacitor of conducting open-work sheet material extending longitudinally of said conductor and curved about said conductor and partially surrounding the same, means for insulating said capacitor from said conductor, and a lighting element of the gas filled tube type located beneath said capacitor and electrically connected between said capacitor and said conductor.

6. The combination with a transmission line conductor, of a marker for said conductor, said marker comprising a pair of insulators, releasable spring-held clamps securing said insulators to said conductor, an open-work capacitance member mounted on said insulators, a lighting element disposed within said capacitance member, and terminal members for said lighting element,

one of said terminal members being electrically connected with the terminal of one of said insulators secured to said conductor, and the other of said terminal members being electrically connected with the terminal of the other insulator secured to said capacitance member.

5. The combination with a high voltage transmission line conductor, of a capacitor mounted in close proximity to said conductor, a lighting 10 element electrically connected between said capacitor and said conductor and energized by charging current flowing between said capacitor and said conductor, and a high resistance element in parallel with said lighting element to prevent 15 arcing between said capacitor and said conductor in case of failure of said lighting element said resistance element having a sufficiently high resistance when current is flowing therein not to rob said lighting element of enough current to 20 interfere seriously with the operation of said lighting element, yet having sufficient conductivity to prevent arcing between said capacitor and said conductor if said light fails.

8. The combination with a high voltage transmission line conductor, of a pair of lighting elements, means for supplying energy for said lighting elements from said conductor, said means comprising a capacitor in electrostatic inductive relation with said transmission line one of said 30 lighting elements having a lower starting voltage than the other to enable said lower starting voltage element to divert current from the other element and to prevent illumination of said other element during operation of said lower starting 35 voltage element but to permit operation of said other element when said lower starting voltage element fails, said lighting elements being arranged in a certain predetermined relation to each other such that an observer cognizant of 40 that relation may ascertain by observing the light whether the energized element is the one having the higher or the one having the lower starting voltage in order to know whether or not one of the elements has failed.

9. The combination with a high voltage transmission line conductor, of a capacitor disposed adjacent said conductor, a pair of lighting elements of the gas filled tube type electrically connected in parallel between said capacitor and said conductor, one of said elements having a lower starting voltage than the other to divert current from the other when the lower starting voltage element is energized but to permit said other element to be energized when said lower starting 10 voltage element fails, and a high resistance in parallel with said lighting elements to prevent arcing between said conductor and capacitor when both of said elements fail said high resistance being of sufficient amount that current flowing 15 therein will prevent arcing between said capacitor and said conductor when said capacitor and conductor are otherwise disconnected but will not be sufficient to interfere materially with the operation of said lights.

10. The combination with a transmission line conductor, of a marker mounted on said conductor, said marker comprising an insulator, a releasable spring held clip having said insulator fixed thereto and having relatively movable jaws 25 for removably securing said insulator to said conductor, a capacitor member mounted on said insulator and a lighting element electrically connected between said conductor and said capacitor member, said spring held clip having operating 30 means projecting therefrom and connected to said jaws for opening the same to facilitate application or removal of said marker while said line is energized.

11. The combination with a transmission line, 35 of a capacitor mounted on and encircling said line but insulated therefrom and a lighting element electrically connected between said line and capacitor and energized by charging current flowing between said line and capacitor, said lighting element being disposed within said capacitor, said capacitor being adapted for the passage of light therethrough from said lighting element.

RALPH HIGGINS.
